UNITED STATES PATENT OFFICE.

MAX W. GOLDBERG, OF PORT WASHINGTON, WISCONSIN, ASSIGNOR TO MODERN POURING DEVICE COMPANY, OF PORT WASHINGTON, WISCONSIN, A CORPORATION OF WISCONSIN.

METAL-POURING DEVICE.

Application filed October 31, 1927. Serial No. 230,037.

This invention relates to improvements in metal pouring devices.

Devices of this character are used to convey molten metal from one portion of a foundry to another, and are also used to pour the metal into molds. The device is usually suspended from an overhead traveling crane. When the container has reached a mold, it is usually raised to the proper height for 10 pouring, and after a portion of the metal in the upper part of the container has been poured, it is necessary to raise the container again to maintain the nozzle at a given height to permit a further flow of the metal when the 15 container is further tilted. In other words, as the amount of metal in the container decreases, the height of the container has to be raised correspondingly. As an illustration, we will assume that the container holds metal 20 sufficient to fill ten molds, and we will assume that the molds are of the same height. The container is manually adjusted to the proper height for the first mold. When that has been poured, the amount of metal in the container having decreased, it is necessary to raise the container still higher to obtain a flow 25 of metal for pouring the next mold, and so on until all are poured. A simple way of stating this is that the height of the container must be inversely proportional to the amount 30 of metal remaining in the container to maintain the nozzle at a predetermined height. Heretofore, these various changes in height have had to be accomplished by hand, which 35 was necessarily a great inconvenience.

It is one of the objects of the present invention to provide a metal pouring device which will automatically adjust the height of the container, and thereby permit the proper 40 flow of metal for pouring the molds.

It is a more specific object of this invention to provide compression springs which will be compressed to varying degrees according to the amount of metal in the container, to thereby 45 automatically regulate the height of said container and thereby permit the proper flow of the metal.

It is a further object of this invention to provide adjustable means for varying the 50 normal height of the device.

It is a further object of this invention to provide a frame for supporting the container, which has a rigid guide rod operating be-

tween rollers to eliminate friction in raising and lowering the hanger bar.

55

It is a further object of this invention to provide an improved means for manually regulating the height of the container whenever this is necessary.

With the above and other objects in view, 60 the invention consists of the improved metal pouring device and all its parts and combinations as set forth in the claims, and all equivalents thereof.

In the accompanying drawings, in which 65 the same reference numerals designate the same parts in all of the views:

Fig. 1 is a front elevation of the improved metal pouring device, part being broken away;

70

Fig. 2 is an edge view thereof;

Fig. 3 is a sectional view on line 3—3 of Fig. 1;

Fig. 4 is a sectional view on line 4—4 of Fig. 1, looking in the direction of the arrows; 75 and

Fig. 5 is a sectional view on line 5—5 of Fig. 1, looking in the direction of the arrows.

Referring to the drawing, the numeral 8 designates a pair of supporting rods which 80 are joined together at their upper ends by a connecting member 9. The connecting member is provided with a swiveled hook 10 for connection with a cable or overhead traveling crane. At their lower ends the supporting 85 rods are joined by a guide member 11, having a medial opening 12 to accommodate the hanger bar 13. The upper end of the hanger bar is secured to a slideable guide member 14 which has openings 15 on each side to accommodate the supporting rods 8. Positioned around the supporting rods and between the guide members 11 and 14 are compression springs 16. The hanger bar 13 is provided with perforations 17 to allow for varying adjustments by inserting the bolt 18 in any one of the perforations according to the adjustment desired.

The lower portion of the device comprises a U-shaped frame 19 having hook-shaped 100 lower ends 20. Near the center of the U-shaped frame is a pair of connecting bars 21, their ends being riveted or otherwise secured to the frame, as at 22. Vertically positioned between the connecting bars and the 105 upper part of the U-shaped frame is a guide

bar 23. The guide bar is also secured to the frame 19 and bars 21 by rivets, as at 24. A 5 slidable member 25 comprising two plates positioned on opposite sides of the lower end of the hanger bar and secured thereto by rivets at 26, is adapted to slide vertically along the guide bar 23. The guide bar is received between rollers 27 mounted between the plates of the slidable member 25. The 10 rollers, which are held in place by pins 28, tend to eliminate friction and the resulting wear upon the parts.

The upper portion of the U-shaped frame is composed of a slotted angular bar 29 secured to the sides of the frame by bolts 31 and nuts 30. The hanger bar 13 is slidably positioned in the slotted portion of this bar and operates against the roller 32, which is mounted on the pin 33. Pivotaly mounted 15 on each end of the pin 33 on each outer side of the frame, is a link member 34. The link members are pivotaly connected at their other ends to lever members 35. The lever members are rigidly connected to a trans- 20 verse shaft 35' which is pivoted to the lower end of the hanger bar and to the slidable member 25. One of the lever members has connected thereto a handle 36. The lever members are arranged to slide the member 25 along the guide bar 23 to raise or lower the frame. An adjusting screw 37 limits the movement of the lever arm to prevent it from going past the center line of the frame. The lower portion of the hanger bar is formed 25 with teeth 38 which are engaged by the pawl 39, and said pawl is pivoted in the slotted bar 29. The pawl is normally held in engagement by a spring 40, and may be swung out of engagement by operation of the pawl lever 41. When the pawl is in engagement with the teeth, the U-shaped frame is supported upon and prevented from dropping any lower upon the hanger bar.

Suspended by the hook-shaped portions 20 45 is the mechanism 42 for carrying and tilting the container 43.

The operation of the device is as follows: When the container is filled with molten metal, there is a downward pressure exerted 50 upon the guide member 14 which compresses the springs 16 and causes a lowering of the entire device. The device is then brought near the molds which are to be filled. By releasing the pawl 39 and operating the lever handle 36, the container is lowered to the proper height for pouring the first mold. The pawl is then released and it springs into engagement with the teeth of the hanger bar, holding the device at the desired height. 55 The container is then tilted by the tilting mechanism 42 to pour the molds. As the amount of metal in the container decreases, a greater height of the container is necessary to maintain the nozzle of the container 60 at the proper height in order for the metal

to continue to flow. This is taken care of automatically by the compression springs 16. With the decreasing weight upon the springs, as the quantity of metal is reduced by pouring, the springs expand nearer to 70 their normal position, and the container is correspondingly raised. Thus a means is provided for automatically regulating the height of the nozzle of the container to continue the flow of the metal as its quantity is 75 reduced.

From the foregoing description, it will be seen that the improved metal pouring device is simple in construction and operation, and is well adapted for the purpose described. 80

What I claim as my invention is:

1. A transporting device comprising a lower frame, a vertical bar within said frame, a slidable member on said vertical bar, a hanger bar having its lower end connected to the slidable member and its upper end to a supporting means, and lever means for raising or lowering the lower frame on the hanger bar. 85

2. A transporting device comprising a lower frame having a slotted upper portion, a vertical bar within said frame, a slidable member on said vertical bar, a hanger bar having its lower end connected to the slidable member and its upper end to a supporting means, the said hanger bar being slidably positioned within the slot of the upper portion of the frame, a link member having one end pivoted to the frame, a lever member pivoted to the other end of the link member and also pivoted on the slidable member for raising or lowering the lower frame on the hanger bar. 90

3. A transporting device comprising a U-shaped frame having a transverse connecting bar, a vertical bar between the transverse bar and the upper portion of the U-shaped frame, a slidable member on said vertical bar, a hanger bar formed with teeth having its lower end connected to the slidable member and its upper end to a supporting means, a lever for raising or lowering the U-shaped frame on the hanger bar, and a pawl on the upper portion of the frame for engaging the teeth of the hanger bar to releasably hold the frame in the desired position. 105

4. A transporting device comprising a portable frame having means for holding the material to be transported, automatic means for regulating the elevation of the material holding part, and manual means for further regulating the elevation of the material holding part without interfering with the automatic regulating means. 120

5. A transporting device comprising a portable frame having means for holding the material to be transported, spring means for automatically regulating the elevation of the material holding part, and lever means for manually regulating the elevation. 125

tion of the material holding part without interfering with the automatic spring regulating means.

6. A transporting device comprising a lower frame, a vertical bar within said frame, a slidable member on said vertical bar, friction reducing means on said slidable member, a hanger bar having its lower end connected to the slidable member and its upper end to a supporting means, and means for raising or lowering the lower frame on the hanger bar.

7. A transporting device comprising a lower frame, a vertical bar within said frame, a slidable member on said vertical bar, roller guides on said slidable member on each edge of said vertical bar, a hanger bar having its lower end connected to the slidable member and its upper end to a supporting means, and means for raising or lowering the lower frame on the hanger bar.

8. A transporting device comprising a lower frame having a slotted upper portion, a vertical bar within said frame, a slidable member on said vertical bar, roller guides on said slidable member and in the slotted upper portion of the frame, a hanger bar having its lower end connected to the slidable member and its upper end to a supporting means, the said hanger bar being slidably positioned within the slot and against the roller of the upper portion of the frame, and means for raising or lowering the frame on the hanger bar.

9. A transporting device comprising a lower frame, a vertically movable member in connection therewith, a hanger bar having a portion connected to the vertically movable member and another portion to a supporting means, and lever means for raising or lowering the lower frame on the hanger bar.

10. A transporting device comprising a lower frame, a slidable member in connection therewith, a hanger bar having a portion connected to the slidable member and another portion to a supporting means, and lever means for raising or lowering the lower frame on the hanger bar.

11. A transporting device comprising a supporting means, a lower frame, and means for adjustably connecting said lower frame to said supporting means, said adjustable connecting means permitting variation in the normal length of the device to adapt it for different headrooms.

12. A transporting device comprising a supporting means, a lower frame, connecting means between said lower frame and said supporting means having a plurality of perforations therein, and means adapted to pass through any one of said perforations for securing the connecting means to the supporting means, said last mentioned means permitting variation in the normal length of the device to adapt it for different headrooms.

In testimony whereof, I affix my signature.
MAX W. GOLDBERG.
